UNITED STATES PATENT OFFICE.

HYMAN BERSON, OF BROOKLYN, NEW YORK.

PAINT SET.

1,295,956.

Specification of Letters Patent.

Patented Mar. 4, 1919.

Application filed September 25, 1918. Serial No. 255,708.

To all whom it may concern:

Be it known that I, HYMAN BERSON, a citizen of the United States of America, residing at Brooklyn, Kings county, and State of New York, have invented certain new and useful Improvements in Paint Sets, of which the following is a full, clear, and exact description.

This invention relates to improvements in paint-sets and has for an object to provide a paint set consisting of a box, preferably cardboard, having depressions in which paint in liquid form is poured in and allowed to dry, the paint being held in the said depressions in a manner hereinafter described. My invention is mainly directed to an inexpensive structure of the character above mentioned, as owing to the difficulty of obtaining suitable metal and also owing to the high cost of same, I preferably form the box or container and its cover out of cardboard.

A further object of the invention is to provide a knock-down paint-set structure that can be packed within a comparatively small space, that is to say, a number of containers can be placed one upon the other and also the covers in flat condition, and shipped or stored away.

30 I will now proceed to describe my invention in detail, the novel features of which will be pointed out in the appended claim, reference being had to the accompanying drawing, wherein:—

35 Figure 1 is a top plan view of the blank out of which the body of the box is formed;

Fig. 2 is a longitudinal sectional view of the body of the box after having been formed;

40 Fig. 3 is a side view of the body of the box, the cover therefor being illustrated in section;

Fig. 4 is an enlarged sectional detail view, the section being taken on a line 4—4 in Fig. 1;

45 Fig. 5 is an enlarged fragmentary detail view illustrating the manner of securing the turned over portions of the body-blank and cover-blank to retain them in box-formation;

Fig. 6 is a similar view illustrating a portion of the blank for the cover of the box, and

50 Fig. 7 is an enlarged sectional view illustrating a modified form of well to retain paint.

My invention comprises a box-body portion 8 and a cover 9 therefor. The body portion 8 is formed out of a blank comprising a bottom 10, having integral therewith side and end-members 11 and 12, the blank being scored at 13 and 14 to enable the side and end-members 11 and 12 to be turned up to form the body portion 8 of the box. After the side and end-members have been turned up they are secured together at the ends preferably by a staple or wire clamp 15 consisting of a wire, the ends of which are forced through the material of the blank and clenched on the inside. Both the body of the box and its cover are formed in a similar manner, the cover being formed out of a blank, the sides and ends of which may be turned up and secured at their ends by staples similar to the staples 15. In Fig. 6, the sides of the cover-blank, which are turned up, are indicated by 16 and the ends by 17. To retain paint, such as water-colors (for instance), I provide the bottom 10 of the body of the box with wells 18 to retain the paint indicated by 19. It will be understood that each well 18 will contain some selected color different from the rest and each well will have stamped adjacent thereto the color which it contains, as indicated at 20, Fig. 1. This feature enables a child to become familiar with the different colors by name. The bottom of the box will be further provided with mixing-wells or pans 21, which are also stamped into the bottom 10 of the box. The mixing-pans will be preferably identified by having stamped therein such indication as illustrated in Fig. 1.

One of the advantages of this structure is that it can be shipped flat, and set up at will. The paint will of course be placed in the wells before shipment. But this does not interfere with the stacking of the blanks.

If desirable, the wells may be formed deep enough to cause the top surface of the paint to lie slightly below the upper surface of the bottom of the box, as shown in Fig. 7; hence the paint will not come into contact with a super-imposed blank when a number of said blanks are piled one upon the other.

One of the advantages of employing cardboard is that the paint will readily adhere thereto and be permanently retained in the depressions or wells; hence during shipment they will not be displaced and cracked by

rough handling. The paint may be poured into the wells or depressions while in wet condition and allowed to dry therein, but it may be molded into blocks and then pasted in said depressions, or otherwise suitably retained therein.

Owing to the fibrous nature of cardboard, the paint, when poured into the wells, will soak into the interstices and when cooled or becomes hard will be firmly bound to the board and cannot be removed by jarring or rough handling. Aside from the comparative low cost of manufacture, these paint-boxes made of cardboard have a great advantage, from the fact that the material is fibrous and the paint will become firmly

affixed thereto. In fact for all intents and purposes, they become integral with the box.

What I claim as my invention is:—

In a paint-set, a box comprising a card-board bottom member having depressions therein containing paint in dry form, turned up side and end-members integral therewith, staples securing the turned up side and end-members together, and a cover for said box.

Signed at New York city, N. Y., this 24 day of September, 1918.

HYMAN BERSON.
